UNITED STATES PATENT OFFICE

95,685

DESIGN FOR AN ELECTRICALLY DRIVEN VARIABLE SPEED POWER UNIT

Don Heyer, Los Angeles, Calif., assignor to United
States Electrical Manufacturing Company, Los
Angeles, Calif., a corporation of California

Application December 26, 1934, Serial No. 54,607

Term of patent 14 years

To all whom it may concern:

Be it known that I, Don Heyer, a citizen of the United States and a resident of the city of Los Angeles, in the county of Los Angeles and State of California, have invented a new, original, and ornamental Design for an Electrically Driven Variable Speed Power Unit, of which the following is a specification, reference being had to the accompanying drawings, forming part thereof, in which:

Figure 1 is a side elevation of the power unit

constructed in accordance with the invention;

Figure 2 is an end elevation taken from the left hand side of Figure 1 with the drive shaft shortened; and

Figure 3 is a plan view taken from the top of Figure 2.

I claim:

The ornamental design for an electrically driven variable speed power unit substantially as shown.

DON HEYER.
